UNITED STATES PATENT OFFICE.

CURTIS L. HOWSE, OF DETROIT, MICHIGAN, ASSIGNEE TO CRAIG DAMPER REGULATOR COMPANY, A CORPORATION OF DELAWARE.

PRESSURE-CONTROLLED MEANS FOR MOTOR REGULATION.

Application filed March 2, 1922. Serial No. 540,650.

To all whom it may concern:

Be it known that I, CURTIS L. HOWSE, a subject of the King of Great Britain, residing at Detroit, in the county of Wayne and 5 State of Michigan, have invented certain new and useful Improvements in Pressure-Controlled Means for Motor Regulation, of which the following is a specification.

My invention relates to motor regulation, 10 and more particularly to the regulation of an electric motor consistently with variations of fluid pressure to which it is desired that speed of the motor should respond. Illustratively I have herein shown my invention as embodied in fashion to regulate 15 an electric motor which drives the blast fan of an underfeed stoker, it being desirable in such an organization that, as boiler pressure rises, the motor shall drive the fan at 20 lower speed, and as boiler pressure is lowered the motor shall drive the fan at higher speed.

Among the particular objects of my invention are to provide a very positive, efficient and sensitive control, insuring power 25 actuation of the fan-motor rheostat consistently with boiler pressure variation, by a fluid motor which itself is sensitively governed from the boiler pressure.

30 Other and further objects will become apparent to those skilled in the art from the following description taken in conjunction with the accompanying drawings wherein I have illustrated a single embodiment of my 35 invention, mainly in diagrammatic form for purposes of clarity.

In said drawings Fig. 1 is a side elevation with parts broken away diagrammatically illustrating the embodiment of my 40 invention in a fan motor regulator for an underfeed stoker; Fig. 2 is an enlarged view of some of the parts.

In the construction illustrated the boiler 10 is served by an underfeed stoker 11 to 45 which air is variably supplied by fan 12 driven by electric motor 13, which, for present purposes, may be of any conventional type such as a three-phase motor.

Motor speed is controlled by a suitable 50 rheostat device 14, shown as movable clockwise to cut in resistance and oppositely to cut out resistance, the movable contact element being biased by a weight 15 on rheostat operating lever 16 to tend to move 55 clockwise. A chain 17 working on the sector

surface 18 of said lever is operated on by the piston of a fluid motor 19 to shift the rheostat counterclockwise. This motor, in the form shown, comprises piston 20 travelling in cylinder 21 into the upper end of 60 which fluid under pressure,—preferably a small stream of water—is admitted through supply pipe 22, such supply being constantly maintained. The wall of the cylinder is perforated with numerous eduction 65 ports 23 all communicating with a vertical passage 24 opening at its lower end to a waste-connection 25, this passage containing the vertically sliding, passage-closing valve 26 of cylindrical rod form which enters the 70 passage from the upper end which, by depression, may progressively seal any number of the lateral ports 23 beginning with the top. Manifestly, to whatever position below the level indicated in Fig. 2 this 75 stopping valve may be depressed, water pressure above the piston will cause the piston to travel down until it opens a lateral port 23 below the extremity of the valve 26 to permit constant escape of the fluid. On 80 the other hand, as valve 26 is raised, opening further ones of the vertical ports giving an excessive escape-opening for the fluid, the weight 15 will pull the piston upward until the condition is re-established 85 where fluid-escape just takes care of fluid-admission.

In conjunction with such a power regulator-engine, accurately controllable by the vertical shifting of its valve stem 26, I 90 provide valve-actuating means responsive to boiler-pressure conditions, and, preferably in the same mechanical train I provide electrically responsive means for abnormally operating the motor to permit return of the 95 rheostat to full-resistance position in the event of rupture of the supply-line for the motor.

From the steam boiler 10 a pressure supply pipe 30 is led to the casing of a pressure-responsive device such as a casing 31 for a diaphragm 32 which acts, through a leverage system, to move the controlling valve 26 of the fluid motor. The knife-edge lifting stem 33 of the diaphragm works on the multiplying lever 34 which is fulcrumed at 35 and suitably weighted as at 36. This lever carries an extension lever 37 linked as at 38 to the motor valve 26. By 100 suitable proportioning of weights, this 105 110

mechanism may be made very sensitive to pressure-changes affecting the diaphragm 32, and, all parts being very freely movable and practically incapable of sticking or developing substantial friction, the movements of all parts are strong, smooth and powerful. Further, it will be noted, by so proportioning the port-spacing 23 of the fluid motor for the rheostat that movement from one 10 port to another of the piston is just sufficient to correspond with movement of a rheostat arm from one contact to the next, insurance of regulation to the finest degree for which the rheostat is capacitated is 15 afforded.

While, in normal operation, extension lever 37 may be regarded as rigidified with lever 34, it is desirable that the extension lever be independently operable fully to 20 retract the valve 26 of the fluid motor should the supply circuit for the electric motor be interrupted, thus permitting the rheostat to go back to full-resistance position. Thus, extension lever 37 is fulcrumed as at 40 on 25 lever 34 and a magnet 41 is mounted on frame 42 carried by lever arm 34 as a means for imparting independent movement to the extension lever 37. This magnet has suitable connection 43 with a suitable portion of 30 the wiring 44 for the electric motor 13, and while energized the magnet holds its heavy armature 45 permanently raised. Upon interruption of current to the magnet, however, it drops its armature 45 which is unit- 35 ed as by pin and slot connection 46 with the end of extension lever 37 so that the falling weight of the armature lifts the active end of the extension lever and fully retracts the valve 26 for the fluid motor.

40 In operation, assuming the parts to be in substantially the mid-position shown, under normal steam pressure of the boiler 10, rise in boiler pressure, communicated to the diaphragm chamber 31 will cause the diaphragm to lift the lever 34 and its extension 45 37, so raising the sliding valve 26 for the fluid-motor and, by opening a higher one of the ports 23, will permit the weight 15 of the rheostat device to draw the piston 20 50 upward, turning the contacts of the rheostat and cutting resistance into circuit of the electric motor 13. Consequently the motor will drive the blast fan 12 at a decreased speed. Should boiler pressure drop, reverse 55 operation will occur, the diaphragm 32 of the pressure-responsive device yielding to the weight 36 of the lever arm 34, the extension 37 whereof will force down the valve 26 for the fluid motor, the piston of which 60 will then seek a lower level, raising the rheostat weight and turning its contact arms counterclockwise to cut out resistance, so speeding up the electric motor 13 and the fan 12. Should the motor circuit be broken, 65 deenergization of magnet 41 will drop the

armature weight on the extension lever 37, rocking it on its pivot 40, and so causing valve 26 to be retracted to maximum extent, permitting the rheostat to go back to maximum-resistance position.

70 While I have herein described in some detail a particular embodiment of my invention it will be seen that many changes in details of construction and arrangement may be made without departure from the spirit 75 of my invention within the scope of the appended claims.

I claim:

1. The combination with a source of supply of variable fluid-pressure, an electric 80 motor to be speed-varied according to variations of the fluid-pressure and means for effecting such motor-speed variations including a movable part for long throw; of means constantly urging said part in one direction; means for exerting power to move said part in the opposite direction or hold said part stationary against the opposing constant urge, as the case may be, said means comprising a piston, a cylinder therefor 85 having provision for constant liquid supply to one end thereof, and long-throw valve means for permitting liquid escape from the cylinder only when the piston is at different distances from the cylinder end determined by the movement of said valve; pressure-responsive means connected with said source of variable fluid pressure and having a diaphragm member displaceable to varying small distances substantially accordantly with pressure variation acting thereon; and a multiplying lever 34 between said diaphragm member and the valve means for said cylinder to vary the position 90 at which said valve means will permit liquid escape from the cylinder progressively throughout the range of piston travel, whereby the piston may dwell at progressively different points in its range of travel substantially accordantly with the variations in fluid pressure and the movable member of the means for effecting motor-speed variation may dwell in accordantly regulated position.

105 2. The combination with a source of supply of variable fluid pressure, an electric motor to be driven at variable speeds according to variation of said pressure, and motor-speed-controlling means having a movable part; of means for moving said movable part to and retaining it in any adjusted position, comprising a motor having a piston operatively connected with said movable part and having a long-throw 110 valve to control, in any of its positions of adjustment, the resultant position of said piston; a pressure-responsive device connected with the source of variable pressure; and operative connections between said pressure-responsive device and said valve in- 115 120 125 130

cluding two members and an electro-responsive device that is in the electric motor circuit, said electro-responsive device when energized rigidifying said member and 5 when de-energized releasing said members for relative movement, thereby to free said valve for movement independently of the pressure-responsive device.

3. The combination with a source of supply of variable fluid-pressure, a motor to be driven at variable speeds according to variations of said pressure, and a speed-controlling rheostat for said motor having a movable element, of means for governing 10 the position of said element including a piston connected with said arm, a hydraulic

cylinder for said piston having provision for liquid supply, and a valve movable to control the position of said piston in the cylinder, a pressure-responsive device connected with the source of variable pressure, and operating connections between said pressure-responsive device and said valve including two levers pivotally connected and an electro-responsive device normally 15 rigidifying said levers and adapted to release one said lever for pivotal movement on the other to free said valve for movement independently of the pressure responsive device.

CURTIS L. HOWSE.
